United States Patent Office.

STEPHEN SCOTTON, OF RICHMOND, INDIANA.

Letters Patent No. 77,662, dated May 5, 1868.

IMPROVEMENT IN TREE-BOXES.

The Schedule referred to in these Letters Patent and making part of the same.

TO WHOM IT MAY CONCERN:

Be it known that I, STEPHEN SCOTTON, of Richmond, Wayne county, and State of Indiana, have made new and useful Improvements in "Tree-Boxes;" and I hereby declare the following to be a full and exact description of the same, reference being had to the drawings that accompany and form a part of these specifications.

The object of my invention is to provide a box or device for the protection and support of young trees, designed not only to secure them from damage by horses or cattle, but also to keep them upright, and prevent their being swayed about or broken by the wind.

Figure 1, perspective view.

Figure 2, view of jointed band, by which the slats are held in position.

Figure 3, sectional view, showing the braces or support for the tree.

Letter A, one section of the band.

Letter B, another section, of different form.

Letters C C', joint or fastening for the ends of the band.

Letter D, wooden slats.

Letters E E, braces to support the tree and keep it upright.

By reference to the drawings, it will be seen that there are three differently-formed sections in the band, each intermediate one being provided with-lugs or projections, as shown at A, fig. 2, so that when the sections are united and formed into a circle, these lugs grasp the edges of the slats D and hold them firmly.

The parts C and C', connecting the bands, are so arranged, that whenever the band becomes loose by the shrinking of the wooden slats or otherwise, it may be tightened by bringing the parts C and C' closer together. To the part C, I attach two pins, *n n*, two holes being made in C' to admit them when the two parts are brought together, and the ratchet *l*, as seen in fig. 2, serves to hold them.

The braces E E are provided with ratchet-teeth, so that they may be moved back and forth in the openings prepared for them, as shown in figs. 2 and 3, and adjusted to the size of the tree.

These sections, A and B, are connected together by a hinge-joint formed by the bolts, *ff*, attached to each end of the section A. On each of the bolts *ff* is a small shoulder, as seen at *h*, in fig. 2, and a small slot, *i*, in the openings *k* in section B. This allows the bolt with its shoulder to enter the opening when the sections are arranged in a straight line, but, when brought into a circle to surround and form the box, the shoulder *h* passes by the slot *i*, and keeps the two sections united.

The sections forming the band surrounding and supporting the slats D, I make of cast iron, and should be uniform in size and shape, so that each section will fit in its corresponding place. This enables us to increase or diminish the size of the box, by adding or deducting sections A and B and the slats D, as we may desire.

What I claim, and desire to secure by Letters Patent, is—

A band or belt, constructed of the various sections, A, B, and C, formed substantially as described, and for the purposes set forth.

The braces E, in combination with the band, substantially as and for the purposes specified.

In testimony whereof, I have signed my name to this specification in the presence of two subscribing witnesses.

STEPHEN SCOTTON.
